HEAD OF AN AEROSOL VALVE

Ralph K. Boyer, Cleveland, and Henry W. Krohn, Jr., North Olmsted, Ohio, assignors to The Dill Manufacturing Company, Cleveland, Ohio, a corporation of Ohio

Application May 8, 1953, Serial No. 24,917

Term of patent 14 years

(Cl. D62—2)

To all whom it may concern:

Be it known that we, Ralph K. Boyer and Henry W. Krohn, Jr., citizens of the United States and residents, respectively, of Cleveland, county of Cuyahoga and State of Ohio, and North Olmsted, county of Cuyahoga and State of Ohio, have invented a new, original, and ornamental Design for a Head of an Aerosol Valve, of which the following is a specification, reference being had to the accompanying drawing forming a part thereof, in which:

Fig. 1 is a front elevational view of a head of an aerosol valve showing our new design;

Fig. 2 is a top plan view;

Fig. 3 is a bottom plan view;

Fig. 4 is a side elevation; and

Fig. 5 is a rear elevation.

We claim:

The ornamental design for a head of an aerosol valve, substantially as shown.

RALPH K. BOYER.
